UNITED STATES PATENT OFFICE.

OLIVER H. SMITH, OF SLATEFORD, PENNSYLVANIA, AND JOSIAH L. SMITH, OF SOUTHERN PINES, NORTH CAROLINA.

MEANS FOR THE INTERCHANGE OF MESSAGES BETWEEN A STATION AND A MOVING CAR.

1,083,866.

Specification of Letters Patent.

Patented Jan. 6, 1914.

Application filed August 18, 1913. Serial No. 785,392.

To all whom it may concern:

Be it known that we, OLIVER H. SMITH, a citizen of the United States, and a resident of Slateford, in the county of Northampton and State of Pennsylvania, and JOSIAH L. SMITH, a citizen of the United States, and a resident of Southern Pines, in the county of Moore and State of North Carolina, have invented a new and Improved Means for the 10 Interchange of Messages Between a Station and a Moving Car, of which the following is a full, clear, and exact description.

This invention relates to mechanism of the character set forth in our previous Patent, No. 1,042,983, issued to us on October 29, 1912.

Among the objects of this invention is to provide a means of simple and more reliable nature for the interchange of messages than 20 has heretofore been possible.

More specifically stated, we provide a system of tubing leading from a railway station or other building in the proximity to a railway track, such tubing being adapted 25 to deliver carriers to and from a car, such carriers being received and deposited by the car as it moves along.

The foregoing and other objects of the invention and the means for carrying out 30 such objects will be hereinafter more fully described and illustrated in the accompanying drawings forming a part of this specification in which like characters of reference indicate corresponding parts in all the 35 views, and in which—

Figure 1 is a side elevation of the principal operating parts, the car and station being in section; Fig. 2 is a side view of the carrier station partly in section on the line 40 2—2 of Fig. 3; Fig. 3 is an elevation at right angles to Fig. 2 partly in section on the line 3—3 of Fig. 2; and Fig. 4 is a plan view of a carrier arm hinged to the car.

The several parts of the device may be 45 made of any suitable materials and the relative sizes and proportions, as well as the general design of the same, may be varied to a considerable extent without departing from the spirit of the invention hereinafter 50 specifically claimed.

Referring more particularly to the drawings, we show at 10 a fragment of a railway 11 station or signal tower along which a car 12 is adapted to move on a railway track 12.

As in our previous patent above noted we 55 provide tubes 13 and 14 leading from and toward the building 10 respectively, and communicating with the compartment of the building indicated at 10^a in proximity to the station master or operator. Adjacent the 60 outer ends of the tubes 13 and 14 we provide what may be termed a carrier station or a place where message carriers 15, shown in the form of hollow balls, may be transferred either from one tube to the other, from one 65 tube to the car, or from the car to the other tube. This carrier station comprises the flaring mouth 16 at the upper end of the tube 14, and a hood 17 over said mouth 16 and through which the delivery end of the 70 pipe 13 passes. The hood 17 may be supported in position by flexible arms 18 extending upwardly from the ground or from the tube 14.

The carrier 15, which the station master 75 wishes to despatch to a moving car, will be dropped by him into the tube 13, whence it passes to and is received by a cradle 19 pivoted at 20 within the hood. Said cradle at its lower end is provided with a fork which 80 normally lies or reaches within the end of the tube 13 in the path of the carrier. A light coil spring 21 may be employed for the purpose of maintaining this normal position. The carrier, when received by the 85 cradle, swings the latter downwardly, as shown, where it will be received by a catcher 22 at the outer end of an arm 23 hinged to the car at 24. The relation of the catcher to the carrier station is indicated in Fig. 2, and 90 the arrow shows the movement of the catcher toward said station. The catcher includes, in connection with the outer end of said arm, a pivoted jaw 25, the front end of which passes over the top of the carrier 15, 95 guiding the carrier relatively rearwardly into a shallow pocket or groove 23' at the outer end of the arm. The carrier will be caused to come to rest in said pocket by means of a stop 26 and will be embraced at 100 its upper side by a convex portion 27 of the jaw so that when the arm 23 is swung upwardly toward the side of the car, as shown in dotted lines in Fig. 1, the carrier will roll freely along said groove 23' until it strikes a stop 28 at a point designed to guide the carrier into a chute 29 leading into a basket 30 within the car. It will be under-

stood, therefore, that the carrier, when received in the pocket 23', will not be gripped by the jaw but will be free to roll therefrom. A spring 31 on one side of the pivot 32 and a spring 33 on the opposite side thereof tend to maintain a substantially uniform position of the jaw and permit sufficient flexibility of the catcher for its purposes. The arm 23 is adapted to be swung upwardly toward the car by means of a bell crank 34 and a hand lever 35 is connected thereto by means of a link 36.

For a message to be delivered from the car, the messenger in the car will lift the arm so that he may insert the message carrier 15 between a pair of fingers 37 at the rear end of the catcher and the rear end of the jaw, as shown in Fig. 2. Said fingers 37 are sufficiently light and flexible to permit the carrier held thereby to be snapped therefrom by the force of the jaw when subjected to the carrier to be received in the pocket 23', as above described. In other words, the carrier to be delivered from the cradle 19 will lift sufficiently upon the front end of the jaw to cause the rear end thereof to force the other carrier through the fingers 37 and into the mouth 16 of the receiving tube 14. Said carrier rolls along the tube 14 and is delivered therefrom to the station master by means of the devices covered by our previous patent above referred to.

A stop 38 is adapted to slide inwardly at the delivery end of the pipe 13, as shown in Fig. 2, for the purpose of retaining within the tube 13 a carrier delivered into said tube after the one which is received by the cradle has been delivered. Since the cradle occupies normally its elevated position so as to receive a carrier, the stop 38 is normally retracted out of the path of the tube 13, said retracting being accomplished by means of a finger 39 above the pivot 20 of the cradle, said finger coöperating with a pair of studs 38' at the adjacent end of said stop. When, however, the cradle swings downwardly under the weight of a carrier, the finger 39 will cause the stop to slide into the position shown. By reason of this construction, the station master may deliver a carrier into the tube 13 for one car and almost immediately thereafter he may follow it up with another carrier which will be retained in the tube 13 and be received and delivered by the cradle after the first carrier has been delivered.

If it should be desired that a carrier containing a message delivered through the tube 13 is to be returned to the one who has sent it without being delivered to a car, the operator may draw upon a finger piece 40 within his reach, and through a system of bell cranks and connections acting upon a lever 41, he may release the carrier so that

it may drop into the tube 14. When the lever 41 is operated in the direction of the arrow, Fig. 3, it will act upon a bell crank 19^a, causing the cradle to be lifted so suddenly as to dislodge the carrier, and thereafter the cradle will be restored by the spring 21 to normal position.

It will be observed that in addition to the flexibility of the arms 18 above referred to, we provide curved guides 42 and 43 along the edges of the carrier station parts so as to insure the guidance of the catcher mechanism into proper operative relation to the carrier station for the purposes of the invention.

Having thus described our invention, we claim as new and desire to secure by Letters Patent:—

1. In a device of the character set forth, the combination with stationary delivery and receiving tubes, the mouth of the delivery tube being located in vertical alinement with the mouth of the receiving tube, of means movable into and normally held in the mouth of said delivery tube and adapted to receive therefrom a message carrier, said carrier means being adapted to swing downwardly, after receiving the carrier, away from said delivery tube, a stop controlled by the mouth of the means just described so as to guard the mouth of the delivery tube, and means carried by a car to receive the first mentioned carrier.

2. In a device of the character set forth, the combination with delivery and receiving tubes having their outer ends adjacent each other, a hood associated with the outer end of the delivery tube above the mouth of the receiving tube, said hood being spaced upwardly from said receiving tube, a cradle pivoted within said hood on a horizontal pivot, means to normally hold the cradle in alinement with the delivery tube whereby it will receive a message carrier delivered therethrough, and by which it will gravitate out of alinement with the tube, and means carried by the car to receive said carrier from the cradle while passing between the hood and the mouth of the receiving tube.

3. In a device of the character set forth, the combination with delivery and receiving tubes having their outer ends adjacent each other and in proximity to a railway track, of means to receive a message carrier from the delivery tube and support it just above the mouth of the receiving tube, and a catcher carried by a car adapted to receive said carrier as the car passes said tubes, said catcher comprising a pivoted arm adapted to extend between the adjacent ends of the tubes aforesaid in a horizontal position, and a jaw pivoted on a horizontal pivot upon said arm, said arm and jaw being provided with sockets to loosely receive said carrier.

4. The combination with delivery and receiving means, of a cradle adapted to receive a message carrier from the delivery means and hold it in suspension, and a catcher carried by a car, said catcher comprising an arm adapted to move below the said message carrier, a jaw pivoted above said arm whereby the carrier is received between the arm and the jaw, and a temporary holding device on another part of the arm whereby another carrier will be discharged from the

catcher into the receiving means simultaneously with the delivery of the first mentioned carrier to the catcher.

In testimony whereof we have signed our 15 names to this specification in the presence of two subscribing witnesses.

OLIVER H. SMITH.
